J. B. Mell.
Cotton Picker.

N° 12,635.

Patented Aug 3, 1855.

UNITED STATES PATENT OFFICE.

J. B. MELL, OF RICEBORO, GEORGIA.

COTTON-GIN.

Specification of Letters Patent No. 12,635, dated April 3, 1855.

To all whom it may concern:

Be it known that I, J. B. MELL, of Riceboro, in the county of Liberty and State of Georgia, have invented a new and Improved 5 Machine for Cleaning Cotton; and I do hereby declare that the following is a full, clear, and exact description of the same, reference being had to the annexed drawings, making a part of this specification, in 10 which—

Figure 1 is a longitudinal vertical section of my improved machine, the plane of section being through the center. Fig. 2 is an end view of do with the casing removed in 15 order to show the interior.

Similar letters of reference indicate corresponding parts in the two figures.

This invention relates to a new and improved machine for cleaning cotton, and 20 consists, in the employment or use of a feed card and two brush rollers, arranged and operating as will be hereafter fully shown and described.

To enable others skilled in the art, to make 25 and use my invention, I will proceed to describe its construction and operation.

A represents a case or box, having within it, at its lower part, a roller, B, having teeth (a) somewhat curved projecting from its 30 periphery; and C is a screen formed of curved bars, or wires, placed at one side, and rather below the center of the roller, as shown clearly in both figures. The screen extends entirely across box A, as shown in 35 Fig. 2.

Directly underneath the screen C there is an inclined perforated board, or sieve D shown in both figures.

E is an inclined board at one end of the 40 box, to the lower end of which the upper ends of the bars, or wires composing the screen C are secured see Fig. 1. This board is bisected and partly removed in Fig. 2.

F is a roller having its periphery covered 45 with a card (b) the teeth of which are about one eighth of an inch long, regularly curved from the leather in which they are fixed to their ends, and tapering regularly to their ends. The roller F is placed a short distance 50 above the roller B and rather at one side of it see Fig. 1. The teeth (a) of the roller B do not come in contact with the teeth of card (b) of roller F. The distance between them should be about one half of an inch.

G is a brush roller having teeth (c) and brushes (d) placed alternately on its periph-

ery, as shown in Figs. 1 and 2. The brushes (d) do not touch the roller F, the distance between the brushes (d) and the teeth of card (b) of roller F should be about three 60 thirty second (3/32) parts of an inch; and the teeth (c) do not project quite so far from the roller G as the brushes (d) Fig. 1. The brush roller G is placed above the card roller F and rather at one side. 65

H is a roller having brushes (e) upon its periphery. The roller H is placed above the card roller F and rather at one side as shown in Fig. 1. The brushes (e) as the roller rotates come in contact with the card roller F. 70

I is an inclined plate or board placed over the roller B between it and the roller G. See both figures.

J is a curb placed underneath the rollers B, F. One end of this curb is attached to 75 the inner end of the inclined board D and the opposite end is inclined and forms a discharging board. The curb J is directly underneath. The stroke of these brushes aided by the current of wind generated by roller 80 G effectually separates the seed and dirt from the cotton wool. The cotton wool adheres to the teeth of the card roller F, while the seed and dirt are driven downward to the inclined plate or board I over which they 85 pass and meet the cotton passing through the throat M. This cotton being shaken by the action of roller B in raising it; all the seed and dirt not tenaciously adhering to it pass through it, and through screen C. The 90 cotton wool adhering to the teeth of the card roller F is carried around with that roller until it meets roller H.

The roller H which rotates in a reverse direction from the other rollers, brushes 95 the cleaned cotton from the card roller F, and the cotton passes down the passage N and out of the box A.

In working this machine the speed of 100 rollers B, and F should be the same. The number of revolutions in a given time should depend on the size of the cylinders and the cotton to be cleaned.

The speed of brush rollers G and H should be the same, and the speed of G and H 105 should be from four to six times greater than the speed of B and F.

This machine does its work efficiently, is not expensive to manufacture, and may be adapted to clean perfectly the various 110 kinds of cotton.

The rollers, B, F, are curved to correspond

to the circular form of the rollers as clearly shown in Fig. 1.

K is a curb at the upper part of the box A placed over the card roller F and between 5 the rollers G, H. This curb is so curved as to be concentric with the rollers F G H see Fig. 1.

L is a covering placed over the upper part of the box A.

10 M is the feed passage or throat of the machine, and N is the discharge passage.

Motion is communicated to the several rollers by means of pulleys O and belts P shown by dotted lines in Fig. 1. The edges 15 of the pulleys are seen in Fig. 2. The pulleys are placed upon the axes of the rollers on the outer side of box A gear wheels may be substituted for pulleys if desired.

The rollers B F G rotate in the direction 20 as shown by arrows 1 in Fig. 1. The roller H in a reverse direction as shown by arrows 2 in Fig. 1.

Operation: The cotton to be cleaned is placed in the throat M of the machine, and 25 the roller B carries it around upon the card roller F. The teeth (a) of the roller B

insert themselves in the mass of the cotton, shake and separate it, as it is raised to F. The teeth of the card on roller F insert 30 themselves in the fibers or wool of the cotton and raise it until it comes in contact with brushes (d) on roller G. The cotton is spread over the whole length of roller F, but the seed and dirt will not 35 enter within the teeth of the card (b), but are thrown on the outside of the card, and exposed to the downward stroke of brushes (d) on roller G.

I am aware that card clothing has been 40 used with a rotary brush in a cotton gin and therefore I do not claim them separately or combined; but

What I claim as my invention and desire to secure by Letters Patent is— 45

The combination of the beater B, card cylinder F, brushes G and H and plate J when arranged substantially in the manner described and set forth.

J. B. MELL.
